ABSTRACT

In combination with a plurality of encoders each of which can generate a different pulse duration coded (PDC) signal which uniquely identifies it: a converter responsive to incoming PDC signals supplied thereto from the encoders to derive therefrom corresponding pulse position coded (PPC) signals which also uniquely identify the corresponding encoders; first means to supply said PDC signals from said encoders to said converter; a like plurality of decoders each of which is adapted to respond to the presence of the PPC signal which uniquely identifies the encoder corresponding to it to produce an output signal, each decoder being non-responsive in the absence of the unique identifying signal; and second means to supply said PPC signals from said converter to all of said decoders in parallel.

ENCODER-DECODER SYSTEM

SUMMARY OF THE INVENTION

My invention is directed toward a system employing a plurality of encoders, a like plurality of decoders and a code converter. Each encoder produces a corresponding encoded signal of the pulse duration coded (PDC) type; the converter converts each PDC signal to a corresponding pulse position coded (PPC) signal; and each decoder responds only to the particular PPC signal which is associated with the corresponding encoder.

Typically, each encoder can be associated with a corresponding remote door to produce its encoded signal when the door is opened. Each decoder is not only associated with a corresponding encoder, but also a corresponding display device in a common display panel whereby when all decoders, which are in parallel, receive all PPC signals, each decoder responds only to the presence of the signal of its corresponding encoder to actuate the appropriate display device to inform a user that a door has been opened. This enables one watchman to inspect the condition, open or closed, of a plurality of remotely disposed doors simultaneously.

The converter simplifies the number of components, as well as the expense of same as required in the system by converting or transforming PDC to PPC signals prior to supplying same to the decoders. A very simple decoder can be used with PPC signals whereas a complex and expensive decoder is required when PDC signals are used.

Typically, the encoded signals can be supplied to the converter via existing power lines, although additional cable can be used if desired.

BRIEF DESCRIPTION OF THE DRAWINGS

In the drawings:

FIG. 1 illustrates the wave forms of various signals employed in my invention;

FIG. 2 is a block diagram of my invention;

FIG. 3 is a diagram of a delay circuit as employed in my invention; and

FIG. 4 is a diagram of a coincident circuit as employed in my invention.

DETAILED DESCRIPTION OF PREFERRED EMBODIMENTS

In my invention, a plurality of encoders can be used wherein each encoder is located at a different one of a like plurality of remotely disposed doors. Each encoder will release a particular encoded signal uniquely identifying it when the corresponding door is opened. All encoded signals can take the form of pulse duration coded (PDC) signals.

These signals can be fed over existing power lines or other cable to the input of a converter wherein the PDC signals are converted into corresponding pulse position coded (PPC) signals.

The PPC signals are supplied to the paralleled inputs of a like plurality of decoders. For each encoded PPC signal, there is one and only one corresponding decoder which will respond to its presence to produce an output signal. In the absence of its corresponding PPC signal, the corresponding encoder will be quiescent.

The outputs of the decoders can be coupled to corresponding lamp circuits in a display device having a like plurality of lamps. Each lamp can have a different num-

ber corresponding to a different door and will be lit to indicate that its corresponding door has been opened when and only when the corresponding encoder has produced a PDC signal converted to a PPC signal by the converter and supplied to the corresponding decoder to produce the output signal supplied to the proper lamp circuit.

As shown in FIGS. 1 and 2, encoder 80 can produce a PDC in the form of a signal having first and second pulse components, the second component immediately following the first component in time sequence. The components are pulses having like plurality and have independently controllable durations. These durations constitute a code. One encoder of this type is shown and described in my copending application, Ser. No. 185,971 filed Oct. 4, 1971, entitled "Encoder". One typical signal is shown at 1 in FIG. 1.

More particularly, in the "Encoder" application, a first single shot multivibrator produces a first unidirectional output pulse of given polarity, the pulse duration being determined by a first time constant network of the first multivibrator. A second single shot multivibrator is coupled to the first multivibrator and is responsive to the trailing edge of the first pulse to produce a second unidirectional pulse of like polarity. The duration of the second pulse is determined by another time constant network of the second multivibrator. Means coupled to the outputs of both multivibrators produces a composite or temporal summation of both pulses. The first and second pulses form the first and second components and the summation is the desired signal.

The converter 10 receives PDC signals from all encoders 80 along a power line 82 or other cable. Each such signal is differentiated in the converter to produce a first spike of given polarity, then a pair of spikes, the first of which has reversed polarity, the second of which has the given polarity, then an additional spike of reversed polarity as shown at 2 in FIG. 1. The converter then produces a train of three spaced pulses A, B and C of like duration. The time separation between pulses A and B is proportional to the time interval between the first spike and the first spike in the pair and thus is proportional to the duration of the first component in the original PDC signal. The time separation between the pulses B and C is proportional to the time interval between the first spike in the pair and the additional spike and thus is proportional to the duration of the second component in the original PDC signal. The resultant PPC signal is shown at 3 in FIG. 1. One converter of this type is shown and described in my copending application, Ser. No. 185,969, filed Oct. 4, 1971 entitled "Code Converter".

More particularly, in the "Code Converter" application, apparatus responds to an incoming signal which can be the output signal produced by the "Encoder" apparatus previously described. The output signal is differentiated to produce a first unidirectional spike of first polarity, then a pair of spikes, the first of which has reversed polarity, the second of which has the polarity, then an additional spike of reversed polarity. The period between the first spike and the first spike in the pair is equal to the duration of the first pulse component in the putput signal. The period between the first spike in the pair and the additional spike is equal to the duration of the second pulse component.

A normally non conductive single shot multivibrator, when triggered into conduction, produces an output

pulse of fixed duration which is less than the duration of either pulse component. Means responsible to the differentiated signal and thus responsive to the various strikes passes the second spike in the pair to the multivibrator in such manner as to have no effect on the conduction thereof and passes the first spike, the first spike in the pair and the additional spike to cause each of these three passed spikes to trigger the multivibrator into conduction whereby the desired train of three pulses is produced.

Each decoder constitutes delay circuits 11 and 14, gates 12 and 16 and coincidence circuits 13 and 15. In the decoder, the PPC signals pass successively there through without delay as well as with specified delays. The values of the delays vary from decoder to decoder 15 in correspondence with the corresponding encoded signals. When a decoder receives its designated encoded signal, it generates an output pulse. Otherwise the decoder is quiescent.

FIG. 2 shows a decoder receiving its designated signal and FIG. 1 shows the appropriate wave forms. Basically, pulse A after being delayed in circuit 11 and being inverted in gate 12 arrives at circuit 13 in time coincidence with undelayed pulse B whereby circuit 13 produced a first pulse. This first pulse after being delayed in circuit 14 and being inverted in gate 16 arrives at circuit 15 in time coincidence with undelayed pulse C. Circuit 15 then produces the desired output pulse. All other decoders have one or two different delay periods and thus will not respond to the particular encoded signal shown. In this way each encoder is keyed to its corresponding decoder and to no other.

Referring now to FIG. 3, the delay circuit comprises a one shot multivibrator employing transistors 60 and 61 which is triggered by the leading edge of the first of the two pulses with which it is concerned. The duration of the pulse yielded by the multivibrator is determined by the time constant network employing capacitor 59 and resistor 54 and is set as desired.

FIG. 4 shows a typical coincidence circuit with the output from a gate passing through diode 65 and resistor 63 to the base of transistor 67 and the pulse input (shown as B in the Figure) passing through diode 66 to resistor 63. The junction of these diodes and resistor 63 is connected via resistor 62 to a point of positive potential. This point is connected to the collector of transistor 67. The emitter is grounded through resistor 64. Consequently, the desired output signal is only produced upon coincidence of the gate signal and the pulse as shown.

While I have described my invention with particular

reference to the drawings and to specific embodiments, my protection is to be limited only by the terms of the claims that follow.

I claim:

5 1. In combination with a plurality of encoders, each of which generates, when activated, a different pulse-duration coded (PDC) signal which uniquely identifies the said each encoder;

10 A converter responsive to incoming PDC signals supplied thereto from said encoders to derive therefrom corresponding pulse position coded (PPC) signals which also uniquely identify the corresponding encoders;

first means to supply said PDC signals from said encoders to said converter;

a like plurality of decoders each of which is responsive to the presence of the PPC signal which uniquely identifies the encoder corresponding to said each decoder to produce an output signal, each decoder being non-responsive in the absence of said uniquely identifying signal; and

second means to supply said PPC signals from said converter to all of said decoders in parallel.

2. The combination of claim 1 wherein said first means includes power lines.

3. The combination of claim 2 wherein the PPC signals each employ three spaced pulses of like polarity and width.

30 4. The combination of claim 3 wherein each decoder contains a first delay circuit to delay the first pulse until the second pulse arrives in time coincidence with the delayed first pulse; a first coincidence circuit to produce an output pulse when said second pulse-delayed first pulse coincidence occurs; a second delay circuit to delay the output pulse until the third pulse arrives in time coincidence with the delayed output pulse; and a second coincidence circuit to produce the desired output signal when said delayed output-third pulse coincidence occurs.

40 5. The combination of claim 2 wherein each decoder is provided with means for passing through PPC signals without delay as well as means for passing through PPC signals with specified delays, the values of the delays varying from decoder to decoder in correspondence with the corresponding encoded signals.

45 6. The combination of claim 5 wherein the PDC signals are each constituted by first and second pulses disposed in immediate time sequences, said pulses having like polarity and variable widths.
